MILKING APPARATUS

Application filed October 4, 1929, Serial No. 397,287, and in Belgium March 1, 1929.

The present invention relates to an apparatus for milking, in which the milking cup, made of an elastic material, is subjected to the action of a vacuum existing in a space or 5 chamber between the said cup and a rigid casing surrounding the latter.

As this cup is generally formed of rubber and must be kept under tension during the milking, it is necessary for this cup to be relaxed when the apparatus is not in use, with 10 a view to the preservation of the cup.

For this purpose the invention provides for the milking cup to be kept under tension during milking by bearing against the above mentioned rigid casing, the tension of the said cup being removed during the idle periods of the apparatus.

With this object in view, the cup is secured at one end to the upper part of the casing for example by means of a removable ring and at the other end by means of a member rigid with the said end and adapted to occupy different relative positions with respect to the lower part of the casing, the said 25 member being capable of being employed as a connecting duct leading to the milk reservoir or reservoirs.

This member is rigidly connected with the lower part of the envelope in such a way 30 as to tension the cup, such rigid connection being obtained for example by means of a removable key.

In order to prevent air from entering into the space or chamber between the cup and the 35 casing, a packing is provided between the said tensioning member and the said casing which packing may be formed in one piece with the elastic cup itself.

The accompanying drawing illustrates by 40 way of example and in a non-limiting manner one embodiment of the invention, the single figure showing a sectional perspective view of such embodiment.

The milking cup 2 is held at its upper part 45 by a ring 3 bearing against a flange 4a on a rigid casing 4. At its lower part the cup is rigidly connected with a member 5 which is employed in the arrangement represented as a connecting tube leading towards the milk 50 reservoir, not shown.

This member 5 is formed with a groove 5a in which engages a key 6 holding the said member against the lower part of the casing 4 and maintaining this action in spite of the tension produced in the said cup 2. The vacuum in the space or chamber comprised between the cup 2 and the casing 4 is produced by a suitable machine connected to a pipe 4b. 55

In order to prevent air from entering into the said space or chamber, a packing 7, 60 formed for example of rubber, is wedged between the member 5 and the casing 4 and becomes deformed into the position shown.

It goes without saying that the said packing 7 may be made in a single piece with the cup 65 2, provided that spaces such as 7a are allowed with a view to permitting the free deformation of the packing.

During the idle periods of the apparatus the key 6 is removed, thus permitting the cup 70 to relax and then be removed from the casing 4 together with the members 5, 7 and 3 which are rigid with it.

According to the invention the locking device 6, 5a may be of any kind; for example, 75 the key 6 may be pivoted upon the end of the casing 4 as shown.

What I claim is:

1. A double-walled milking cup having one 80 of its walls elastic and the other rigid, means positioned at the base of the said elastic wall and in axial alignment with the cup formed by said rigid wall for draining the milk, a portion of said milk draining means having an annular groove, and a movable plate engageable in said groove for maintaining said elastic wall under tension when engaged therewith and for releasing said wall to relieve the same from tension. 85

2. A double walled milking cup having one 90 of its walls elastic and the other rigid, means positioned at the base of the said elastic wall and in axial alignment with the cup formed by said wall for draining the milk, said milk 95 draining means having an annular groove and a movable plate engaged in said groove for maintaining said elastic wall under tension when engaged therewith and for releasing said wall to relieve the same from tension, 100

said milk draining means having a second annular groove disposed adjacent the elastic wall and a removable packing disposed in this second groove for forcible engagement with the lower end thereof.

5 In testimony whereof I have affixed my signature.

FERNAND HENRARD.
